UNITED STATES PATENT OFFICE

170,099

TUMBLER OR SIMILAR ARTICLE

Fran Taylor, Canal Winchester, Ohio, assignor to Gay Fad Studios Company, Lancaster, Ohio, a corporation of Ohio

Application March 1, 1952, Serial No. 18,741

Term of patent 3½ years

(Cl. D36—8)

To all whom it may concern:

Be it known that I, Fran Taylor, a citizen of the United States of America, residing at Canal Winchester, in the county of Franklin, State of Ohio, have invented a new, original, and ornamental Design for a Tumbler or Similar Article, of which the following is a specification, reference being had to the accompanying drawing, forming part thereof.

The figure is a perspective view of a tumbler or similar article embodying my new design.

The dominant feature of my design resides in the portions shown in full lines.

I claim:

The ornamental design for a tumbler or similar article, substantially as described and shown.

FRAN TAYLOR.
